UNITED STATES PATENT OFFICE.

MATT BUZZARD, OF FENTON, MICHIGAN.

PNEUMATIC-TIRE INFLATER.

1,222,520.

Specification of Letters Patent. Patented Apr. 10, 1917.

Application filed November 28, 1916. Serial No. 183,997.

To all whom it may concern:

Be it known that I, MATT BUZZARD, a citizen of the United States, residing at Fenton, in the county of Genesee and State of Michigan, have invented new and useful Improvements in Pneumatic-Tire Inflators, of which the following is a specification.

This invention is an improved device for generating acetylene gas and inflating a tire by means of such gas, one object of the invention being to provide an improved acetylene gas generator which is simple in construction, is extremely compact and which can be readily operated and regulated, another object being to provide an improved method of inflating tires and to utilize acetylene gas as a medium for inflating such tires and without the necessity of compressing the gas or employing compressing mechanism.

The invention consists in the construction, combination and arrangement of devices hereinafter described and claimed.

The invention further consists in a method of inflating a tire by generating acetylene gas and conducting such gas while under pressure to an inflatable tire as hereinafter described and claimed.

In the accompanying drawings:

Figure 1 is a central sectional view of an acetylene gas generator for use in inflating tires and constructed and arranged in accordance with my invention.

Fig. 2 is an elevation of one end of the generator.

Fig. 3 is a similar view showing the other end of the generator.

In the construction of my improved acetylene gas generator I provide a pair of vessels 1, 2 which are substantially identical in construction and are shown here as of cylindrical form, of equal diameter, and as provided with an open inner end and a closed outer end. In practice the vessels are preferably castings and may be very cheaply manufactured. A partition disk 3 is arranged to fit in the opposed open ends of the vessels and is provided with an annular flange 4 between the vessels, packing rings or gaskets 5, of rubber or other suitable material being interposed between the flange 4 and the opposed ends of the walls of the vessels. The vessel 2 has a seat 6 arranged centrally on its closed outer end. The vessels are detachably secured together by a hoop or band 7 which passes around them

and which bears on the closed outer ends thereof and is engaged between spaced lugs 8, 9 with which the vessels 1, 2 are respectively provided. That portion of the hoop or band which passes across the outer end of the vessel 1 has an enlarged central circular portion 10 which is provided with a central circular opening 11. An eccentric cam 12 is mounted on the center of the opposite end of the hoop or band as at 13, is adapted to engage in the seat 6 and has a lever handle 14 by means of which said eccentric cam may be turned. When the eccentric cam is in the position shown in Fig. 1 with its lever arm 14 bearing against the outer end of the vessel 2 said cam co-acts with the hoop or band to securely clamp the vessels together and on opposite sides of the partition disk, as will be understood. By turning the eccentric cam in the direction indicated by the arrow the tension on the vessels will be released and the band may be removed from the vessels and the latter separated.

The vessel 1 forms a water reservoir and is provided with a central circular unthreaded opening in its closed outer end for the reception of the enlarged portion 15 of a tube 16. The smaller end of the tube is threaded as at 17 and is screwed through a threaded central opening in the partition disk. At the outer end of the tube is an enlarged head 18 which is peripherally milled and which is arranged in the opening 11 of the hoop or band. By means of this head the tube may be screwed or unscrewed and may be drawn upwardly a slight distance when desired to cause the water from the vessel 1 to pass through the central opening in the partition disk and into the generating chamber formed in the vessel 2 and in which the carbide is placed as indicated at a. A disk 19 is arranged on the vessel 2, on the carbide and co-acts with a spring 20 to hold the carbide compactly in the vessel 2.

A tube 21 of rubber or the like leads from the vessel 2 and is employed for conveying acetylene gas under pressure from the generator directly to a tire for inflating the tire by means of such gas. The gas is generated at such pressure that no compressing means whatever is required when inflating a tire with acetylene gas in accordance with my invention.

A suitable packing ring 22 is arranged between the head 18 of the tube 16 and the

outer end of the vessel 1 to prevent leakage. The tube 22 has its bore normally closed by a valve 23 which is arranged in a seat 24 formed in the enlarged portion 15 of the tube. A coiled spring 25 normally holds the valve in closed position and said spring is held under any desired degree of compression by means of a plug 25' which is screwed in the head 18 as at 26 and which is provided with a central opening 27. The spring closed valve permits acetylene gas to escape from the generator when the pressure of the gas becomes excessive. By means of the valve, the spring and the tension regulating plug the pressure of the gas supplied to the tire may be regulated as may be desired.

While I have herein shown and described my acetylene gas generating device as especially adapted for use for inflating tires I would have it understood that the same may

be used for other purposes as well. I would also have it understood that changes may be made in the form, proportion and construction of the several parts without departing from the spirit of my invention and within 25 the scope of the appended claim.

Having thus described my invention what is claimed is:

An acetylene gas generator comprising a pair of vessels, a partition between said vessels, gas discharge means for one of the vessels, a tube extending through the other vessel and the partition and detachable from the latter to permit the flow of water from said vessel to the other vessel, a valve to close said tube, a spring to hold said valve in closed position, and means to vary the tension of said spring.

In testimony whereof I affix my signature.
MATT BUZZARD.
